UNITED STATES PATENT OFFICE.

WILMOT H. DIGGS, OF BALTIMORE, MARYLAND.

DESIGN FOR A TOOL-SHARPENER.

SPECIFICATION forming part of Design No. 33,329, dated October 9, 1900.

Application filed September 8, 1900. Serial No. 29,469. Term of patent 14 years.

To all whom it may concern:

Be it known that I, WILMOT H. DIGGS, a citizen of the United States, residing at Baltimore, in the State of Maryland, have invented and produced a new and useful Design for Tool-Sharpener, of which the following is a specification.

My invention is a design for tool-sharpeners; and it consists in the shape and configuration illustrated in the accompanying drawings, in which—

Figure 1 is a side elevation of a sharpener embodying the design, and Fig. 2 is a central vertical section of the same.

15 The design comprises a cylindrical body

portion having graduated diameters, as indicated at 1, 2, 3, 4, and 5, and formed with a plurality of annular ribs or projections 6, of varying diameter.

The sharpener is surmounted by a cap 7, 20 having a rounded edge 8.

I claim—

The design for a tool-sharpener herein shown and described.

In testimony whereof I affix my signature 25 in presence of two witnesses.

WILMOT H. DIGGS.

Witnesses:

H. L. REID,

ELLA M. CARNEY.
